CLAIM

The ornamental design for a mixed reality vehicle simulator as shown and described.

DESCRIPTION

FIG. 1 is a front perspective view of a mixed reality vehicle simulator showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a rear perspective view thereof; and,

FIG. 9 is a bottom front perspective view thereof.

The features of the mixed reality vehicle simulator shown in broken lines in the figures form no part of the claimed design.
